UNITED STATES PATENT OFFICE.

ARTHUR N. AMES, OF FRANKLIN, NEW HAMPSHIRE, ASSIGNOR, BY MESNE ASSIGNMENTS, TO COMMERCIAL MACHINE COMPANY, OF FRANKLIN, NEW HAMPSHIRE, A CORPORATION OF MASSACHUSETTS.

THREAD-REINFORCING MECHANISM FOR KNITTING-MACHINES.

1,181,718.

Specification of Letters Patent.

Patented May 2, 1916.

Continuation in part of application Serial No. 635,245, filed June 26, 1911. This application filed September 26, 1912. Serial No. 722,514.

To all whom it may concern:

Be it known that I, ARTHUR N. AMES, a citizen of the United States, and resident of Franklin, in the county of Merrimack and State of New Hampshire, have invented certain new and useful Improvements in Thread-Reinforcing Mechanism for Knitting-Machines, of which the following is a specification.

10 This invention relates to knitting machines, especially of the circular type, the machine being designed particularly for knitting stockings, although I do not limit myself, in all features of my invention, to hosiery-knitting machines. In the following description, however, I shall refer to stockings or hosiery because in such articles of apparel there is more occasion than in any other article, for reinforcing the yarn 15 or thread employed for knitting predetermined portions of the fabric, such as for the heel and toe, to form a double sole, a high spliced heel, or a garter top.

20 The present application is, in part, a continuation of my prior application which became Patent No. 1,052,877, granted February 11, 1913, to which patent reference may be had for description of specific means of operating the mechanism claimed herein.

30 The particular object of the present invention is to provide a simple and reliable twister mechanism for supplying a reinforcing thread to a main thread, for the purpose above described.

35 A further object is to provide with such twister mechanism, means for securing such a uniform pulling tension upon the reinforced thread that there will be no liability of bunching or knotting the reinforcing 40 thread upon the main thread.

To these ends the invention consists in the improvements which I shall now proceed to describe and claim.

45 Of the accompanying drawings,—Figure 1 is a side elevation of the upper part of such a knitting machine as shown in my said patent, the figure being partly broken out to better illustrate the means for rotating the twister. Fig. 2 represents a section 0 on line 2—2 of Fig. 1. Fig. 3 is a plan view of the mechanism shown in Fig. 1, the bracket for supporting some of the mechanism being shown in section. Fig. 4 repre-

sents a transverse section near the gear housing and showing the latter in elevation. 55 Fig. 5 is a detail view of the cutter lever, and coöperating members shown in section.

Similar reference characters indicate the same or similar parts in all the figures.

Two posts 10, 11 are suitably supported, 60 as by a bracket, in the manner explained in my said patent, the upper ends of said posts supporting secured thereto a bracket 12 which supports the horizontal bedplate 13 having an extension 14. A gear housing 15 rotatably supports the tubular twister 16 comprising a circular series of straight pins which project rearwardly and having their ends preferably slightly flaring. By the term "rearwardly" I mean that the projections of the twister extend in a direction opposite to that of the travel of the thread. The object of this arrangement will be explained hereinafter.

The twister 16 has a pinion 17 meshing 75 with a gear 18 secured to one end of a shaft 19, said shaft passing through a bearing aperture in the rear wall of the gear housing, with sufficient freedom of movement, however, to permit the shaft to be slightly 80 oscillated vertically as presently described. The rear end of the shaft 19 has a small friction disk 20 adapted to be engaged by a larger friction disk 21 at the upper end of a shaft 22 which is driven as explained 85 by said patent. When the twister is not to be rotated there will be a slight space between the periphery of the disk 20 and the upper face of disk 21, as presently described. The shaft 22 may be understood at present 90 as to be rotated by any suitable constant driver.

The rear end of the shaft 19 passes through and is supported by a bearing sleeve 23 carried by an elbow lever 24 mounted 95 upon a pivot 25 and having a spring arm 26. The longer arm of said lever is formed or provided with a web 27 having a toe 28 extending under the disk 21. The web 27 is formed with a curved under edge 29, the 100 front end of said web being beveled or inclined as at 30. Coacting with this web, as presently described, is a pin 31 carried by an elbow lever 32 pivoted at 33 to bracket 12 and having a short arm 34. Pivoted 105 connected at 35 to the arm 34 is a link 36

normally held downwardly by a spring 37. The link 36 is connected to one end of a lever 38 (Fig. 3) pivoted at 39 to a collar 40 secured to post 11, and having its other 5 end pivoted to a vertical rod 41 (Fig. 1) the lower end of which is operated by pattern-controlled mechanism such as illustrated in my said patent. The rod 41 is actuated at the proper time so as to rock the lever 32. 10 When the pin 31 of the lever 32 is moved along the curved edge 29, no movement is imparted to the lever 24 which carries the bearing for supporting the rear end of twister-actuating shaft 19. At this time 15 there is slight space between friction disks 20, 21, and at the same time the toe 28 holds the disk 21 and its shaft 22 slightly raised so that the said shaft 22 will not be rotated by its driving mechanism. When the pin 31 moves to the left and reaches the incline 30, the lever 24 is free to move so that the bearing 23 will permit the rear end of shaft 19 to descend, and let the disk 20 contact with disk 21. The toe 28, of course, at the same 20 time permits disk 21 and shaft 22 to drop and be driven. The left-hand edge of the long arm 32 of the lever contacts with spring arm 26 of lever 24 and yieldingly forces the lever 24 in the direction to increase the friction between disks 20 and 21, and at the 25 same time increase the friction drive of shaft 22. Rotation of the shaft 19 causes, of course, rotation of the twister 16 so that the latter will operate in the manner hereinafter 30 described.

When the lever 32 oscillates as described it also actuates a cutter and an inserter which will now be described. Rising from the bedplate 13 is a web bracket 42, the latter having attaching feet 43. (Fig 3). The web 42 is provided with a slot 44 along which slides a pin 45. (Figs. 1 and 2). One end of a link 46 is mounted on the pin 45, and between it and the side face of web 42 40 is a washer 47. The other end of the link 46 is pivoted at 48 to the lever arm 32. It will now be understood that the pin 45 partakes of all movements of the lever arm 32.

A slide plate 49 has slots 50 through 50 which pins 51 pass into the side of web 42. The slide 49 carries a guide tube or inserter 52, the reinforcing thread w' passing through said tube to the twister. The slide 49 also carries a brush 53, the purpose of 55 which will be presently explained. A lug 54 projecting downwardly from the slide 49 is held in contact with the washer 47 by means of a spring 55 so that the slide 49 partakes of all the movements of the lever arm 32 through the link connection thereof with the pin 45 and the washer 47.

The cutter lever 56 is loosely pivoted at 57 to the bracket 42, and at its free or front end has a cutter 58 adapted to co-operate 60 with a cutter block 59 mounted on the bed-

plate 13 so as to sever the reinforcing thread when the said lever 56 is swung downwardly to carry the reinforcing thread against the cutter block 59. The cutter lever is actuated by the following means:—Its lower edge (Fig. 5) is formed with a straight edge 60 and a recess 61. When the pin 45 reciprocates along the straight edge the cutter lever is held up, but when said pin reaches the recess 61 it engages the rear wall of said recess and positively actuates the cutter lever on its pivot 57 to cause the cutter 58 to co-operate with block 59 in severing the thread. 70

The reinforcing thread on its way to the tube 52 passes over a plate 62 having preferably a felt upper surface 63, said plate being carried by the bracket 42. A drop pad 64 carried by a weighted arm 65 pivoted at 66 to an upright or standard has a lateral tongue 67 (Figs. 2 and 5) resting on the top 80 of cutter lever 56. When the cutter lever descends as described, it permits the pad 64 to drop upon the reinforcing thread so as to hold it frictionally during the operation of the cutter. The machine frame is provided with arms having guide eyes 68, 69 for the main and reinforcing threads w , w' respectively. The main thread w passes through a guide eye 70 in bracket 42 and then through a guide eye 71 which is in fixed 85 position with its delivering end slightly inside of the twister 16, so that the main thread can never become engaged by the fingers or springs of the twister. 90

Projecting from the arm or bracket which carries the guide eye 71 is a guard pin 72, the purpose of which is to coat with the brush 53 in causing the reinforcing thread to be inserted or carried between two of the fingers of the twister when the slide 49 is 105 advanced. It is to be understood that when said slide advances it moves farther to the left than shown in Fig. 1, the slots 50 in the slide 49 permitting this extent of movement under the influence of lever 32. When the 110 reinforcing thread is severed by the cutter, the portion of it which is beyond said cutter is, of course, drawn along with the main thread to which it has been applied, while the end in the rear of the cutter remains 115 hanging down from the tube 52 and in contact with the tips of the bristles of the brush 53, the extreme end being, of course, in proximity to the block 59 where it was cut. When the slide 49 advances, this depending 120 or loose end of thread will be carried between two of the fingers of the twister, and then, through the connections already described, the twister immediately begins to rotate and connects the reinforcing thread 125 to the main thread. After this the timing of the operation is such that the slide 49 retreats to the position shown in Fig. 1, and rotation of the twister ceases because of the pin 31 riding along the bevel or incline 30 130

and disengaging the driving elements of the twister. The timing of the operation is such that when the reinforcing thread is to be severed, the arm 32 swings to the right from the position shown in Fig. 1 so that the pin 45 engages the recess 61 of the cutter lever and swings the cutter 58 down to sever the thread, leaving the loose end of the reinforcing thread hanging from tube 52 ready to be inserted into the twister again when the pattern mechanism shall again act upon the lever 32 to swing the latter. An upright 73 carried by extension 14 is provided with a guide eye 74 for the thread, the upper end of said upright being provided with a V-shaped recess (Figs. 3 and 4), into which recess the take-up lever arm passes when lowered, under the influence of the passing thread or threads, and when permitted to do so by the mechanism presently described.

From the take-up arm or lever the main thread, and the reinforcing thread when the latter is applied thereto, passes down through a tubular shaft 76 to the knitting mechanism. The take-up lever arm 77, having a loop or guide at its outer end for the thread, is carried by a yoke 78 pivoted at 79 to a standard 80, the two arms of the yoke being indicated at 81 and 82 in Fig. 1. The arm 81 has a beveled or cam-shaped end which engages a pin 83 projecting from a plunger 84 vertically movable in the standard 80 and co-operating with a stationary clamp block 85. The main thread w^2 passes over the block 85 and under plunger 84. As the tension on the yarn increases, lever 77 will be depressed and the arm 81 acting on pin 83 will raise the plunger 84 and relieve the thread w^2 from the weight of said plunger, thus allowing the supply to be relieved. As the tension on the thread decreases during knitting, the resulting up movement of the lever 77 results in permitting the plunger 84 to descend again on to the thread. In this way the tension on the thread controlled by lever arm 77 is automatically regulated. While knitting with reciprocating motion of the cam cylinder of the knitting machine, the thread from lever arm 77 is alternately tightened and slackened, which causes said lever arm to vibrate up and down so as to take up the slack between said arm and the knitting point and to give slack as may be required in the back and forth movements of the cam cylinder. While taking up slack the plunger is lowered on to the thread to prevent lever arm 77 drawing thread from the supply instead of taking the slack up from the opposite direction. The arm 82 of the yoke engages a pin or roll 86 carried by a bell-crank lever 87 pivoted at 88, the short arm of said bell-crank lever having a rod 89 connected to it. The rod 89 is actuated by pattern-controlled mechanism described in

my said patent to oscillate the lever 87 so that the pin or roll 86 thereof will ride along the arm 82 of the take-up lever arm 77. The rod 89 is provided with suitable yielding resistance against upward movement, as by a spring such as described in the said patent. The long arm of the lever 87 carrying the roll 86 swings in a direction substantially crosswise of the direction in which yoke arm 82 swings. Consequently, as the take-up arm 77 is pulled downwardly by increased tension on the thread being knitted, the movement of the bell-crank lever 87 will be opposed by greater resistance, but the simultaneous reduction in the distance between the pin or roll 86 and the fulcrum or pivot 79 of lever arm 77 will compensate for the increase in the resistance to the movement of lever 77 caused by rod 89 and its connections. As the lever arm 77 rises and lever 87 moves in the opposite direction, the increase of the distance between said pin 86 and fulcrum 79 will likewise compensate for the decrease in the resistance to movement of lever 87 so as to maintain the effective force of such resistance. This action upon and of the lever arm 87 is of particular use in connection with the twister mechanism, because it exerts such a uniform tension upon the thread between guide eye 74 and tubular shaft 76 that there will be no liability of the end of the reinforcing thread which has just been applied being slid along the main thread as it is pulled through the eye of the lever arm 77. If such a sliding along were to occur it would produce a knot or bunch that might result in breaking the thread, or, if it did not break, in leaving a knot or bunch that would show in the fabric.

Owing to the fact that the twister has projections which extend rearwardly, or in the opposite direction from that of the travel of the thread, proper wrapping and reinforcing of the thread around the main thread is insured before the reinforcing thread can be drawn along by the advancing main thread. The reinforcing thread is severed at a point before it reaches the twister and is left in a position where it cannot be either engaged by the twister if the latter should rotate in either direction, or in such position as to be "sucked along" by proximity of projecting fibers of the two threads. This arrangement avoids the necessity of employing clamping or other devices to hold the reinforcing thread in the twister long enough to be wrapped around the main thread. A twister facing or opening forwardly will frequently let the reinforcing thread be pulled along by the main thread prematurely unless clamps or holding devices of some kind are employed to prevent it.

As clearly shown in the drawings, one end of the twister is irregularly formed; that is, one end is not smooth, but has projections

4
 of such character as to positively engage the reinforcing thread and wrap it around the main yarn. For the purposes which I have described herein, it is essential that this irregular end of the twister, or the end having 5 projections, shall be the rear end, by which it is to be understood is meant the end toward the point of supply, or in other words, in a direction the reverse of the direction of 10 the feed of the thread. The structure provides a twister, the entrance end of which is irregularly formed, whereby after the reinforcing thread has been started around the main thread, the travel of the main thread 15 keeps the reinforcing thread in engagement with the projections, or the irregular rear end of the twister.

I believe myself to be the first to provide any construction of twister whereby the 20 travel of the main thread will hold the reinforcing thread in engagement with projections that are adapted to twist the reinforcing thread around the main thread. Therefore, in the appended claims, I mean by the 25 term "projections" to include anything that will positively engage the reinforcing thread and wrap it around the main thread.

By locating the cutter in the rear of the twister, I avoid leaving thread in the twister 30 as heretofore done. Such leaving of the thread in the twister is liable to let the reinforcing thread be applied at the wrong time unless the twister itself is stopped, or holding clamps or devices employed for the 35 reinforcing thread. With my construction the reinforcing thread is never left in the twister or close to the main thread, when reinforcing is not intended. By cutting off the reinforcing thread and letting its front 40 end drop, said thread is removed from proximity to the main thread until positively inserted or carried to position to be engaged by the twister and wrapped a sufficient number 45 of times around the main thread. Therefore the twister may be revolved in either direction, since no reinforcing thread is in it when reinforcing is not intended.

It will be understood, of course, that when 50 the lever arm 77 is pulled down until its shank is in the V-notch 75, said V-notch prevents any lateral movement and holds the said arm with the eye or loop of the latter in proper alignment with the aperture of the tubular shaft 76, said loop or eye being 55 below the plane of the guide eye 74 so that the thread passes with very little friction. At this time the pin or roll 86 of lever 87 is so close to the pivot 79 that there is no increased pull of lever arm 77, although the 60 resistance to the lift of the rod 89 is then the greatest.

The mechanism for rotating the twister is such that although the twister itself is intermittently rotated, the drive mechanism 65 therefor is constant. In the particular em-

bodiment of the invention illustrated, the mechanism for doing this consists of the separable frictional driving devices for the shaft 19. The shaft 22 is itself intermittently driven, but there is a constant driver 70 for said shaft 22. However, whether the shaft 22 is constantly driven or intermittently so, there is a constant driver employed in the machine, while the mounting of the shaft 19 is such that its disk 20 may be intermittently separated from and connected to 75 be driven by the disk 21. The construction is such that when the twister is to be operated, only the inertia of the immediate twister mechanism is to be overcome, and 80 said twister and its immediate operating devices are of such weight that their inertia is quickly overcome when the connections for driving the same are made, and the twister will soon stop rotating when said 85 connections are broken.

It will also be observed that the pin 45 which is reciprocated by the lever 32 constitutes a device which operates both the cutter and the means for actuating the devices 90 for introducing the thread to the twister.

I claim:

1. A reinforcing mechanism for knitting machines, comprising a twister having an irregular end, a cutter adjacent the irregular 95 end of the twister, and means for engaging the front end of the severed thread to facilitate introduction thereof to the twister.

2. A reinforcing mechanism for knitting 100 machines, comprising a twister provided with projections extending in a direction opposite to the direction of travel of the thread, a cutter adjacent the projections of the twister, and a slide having a brush to 105 engage the reinforcing thread.

3. A reinforcing mechanism for knitting machines, comprising a rearwardly-facing twister, a slide having a tube for the reinforcing thread and movable toward and 110 from the rear end of the twister, a brush carried by said slide, and a cutter movable between the tube and the twister.

4. A reinforcing mechanism for knitting 115 machines, comprising a rearwardly-facing twister, a slide having a tube for the reinforcing thread and movable toward and from the rear end of the twister, a brush carried by said slide, a cutter movable between the tube and the twister, and a clamp 120 in the rear of the cutter for holding the thread.

5. A reinforcing mechanism for knitting 125 machines, comprising a rearwardly-facing twister having its rear end irregular, a cutter in the rear of the twister, and a take-up having means for keeping a uniform tension on the thread beyond the twister.

6. A reinforcing mechanism for knitting 130 machines, comprising a twister, a cutter in

the rear of the twister, a take-up arm, and means for controlling said take-up arm having means for preventing the arm from exerting a pull upon the thread to cause knotting of the reinforcing thread upon the main thread.

7. A reinforcing mechanism for knitting machines, having means for guiding a plurality of threads, a twister having an irregular rear end for carrying the free extremity of one thread about another thread, and means in the rear of the twister for engaging the thread and shifting it to position to be engaged by said projections.

15. 8. A reinforcing mechanism for knitting machines, having means for guiding a plurality of threads, a twister having an irregular rear end for carrying the free extremity of one thread about another thread, means in the rear of the twister for engaging the thread and shifting it to position to be engaged by said projections and means for severing the thread in the rear of the twister.

25. 9. A reinforcing mechanism for knitting machines, comprising a twister, a guide eye

for a main thread in the rear of the twister, a stationary transverse pin below the twister, a cutter in the rear of the twister, and means movable below the twister and between it and said transverse pin for carrying the thread into engagement with the twister.

10. A reinforcing mechanism for knitting machines, comprising a rearwardly-facing twister, a cutter in the rear of the twister, 35 a slide having a brush, means for reciprocating said slide toward and from the rear end of the twister, and a transverse guide pin below the brush.

11. A reinforcing mechanism for knitting 40 machines, comprising a twister, a cutter for severing the reinforcing thread, an introducer for connecting the thread to the twister, and a reciprocating member for operating both the cutter and the introducer. 45

In testimony whereof I have affixed my signature, in presence of two witnesses.

ARTHUR N. AMES.
